United States Patent Office.

DENNIS GOODYEAR, OF ITHACA, NEW YORK.

Letters Patent No. 65,560, dated June 11, 1867.

LAST-LOCK.

The Schedule referred to in these Letters Patent and making part of the same.

TO ALL WHOM IT MAY CONCERN:

Be it known that I, DENNIS GOODYEAR, of Ithaca, Tompkins county, New York, have invented a Lock for Holding the Block of Boot and Shoe Lasts to the same; and I do hereby declare that the following is a full and exact description thereof, reference being had to the annexed drawings, and to the letters of reference marked thereon.

Figure 1 is a side view of a last with my lock in it.

Figure 2 is a view of the shank of the last, showing my lock in it; and

Figures 3 are the separate parts of my lock when out of the last.

My object is to make an adjustable fastening or lock for the purpose of convenient separation, and holding together at pleasure the block of the last and the last itself. This I accomplish by a pin or plug placed in a metallic sheath. The plug is made cam-shape. The sheath has a tooth-like projection. When the cam portion of the plug bears on the sheath, the dog or tooth portion is projected and locks the block to the last. And to aid this the hole or excavation in the last is so made as to aid in the end described.

This is apparent in the drawings, where A is the last and B the block, and C my lock. In fig. 2, B is the block, C is my lock, made of the parts D, the handle E, the fastening of the handle to the plug, and F the sheath. In fig. 3 C is my lock, and the parts are more clearly seen, which are D, the handle, and E and F as described, and G the plug, and H the dog or tooth that by the described cam action is thrust into and holds in a proper excavation in the last. And the friction on the sides aids in this.

The use of this device is that the lock is put through the block and into the last, and the projection I on the sheath put into its slot in the block, so that it cannot revolve. Then the plug G is, by its handle, turned so far around that the tooth H enters its cavity in the last, and by the surface J makes friction as described. The other uses of the device are apparent to those skilled in the art to which it appertains.

Claim.

1. I claim the described device, composed of the parts G, the plug or pin F, the sheath and its dog or tooth, and handle D, or other convenient equivalent for turning and thus locking the same in the last as described.

2. I claim the device of a pin or plug thrust through the last-block into the last, and held there by friction, a dog or tooth, or other convenient means, when the locking is done by the cam-like action of the pin or plug, as described.

DENNIS GOODYEAR
